UNITED STATES PATENT OFFICE

LOUIS NYCZ, OF BINGHAMTON, NEW YORK

NONSINKABLE AEROPLANE BODY

Application filed July 17, 1928. Serial No. 293,377.

My invention pertains to nonsinkable vessels and particularly to nonsinkable aeroplane bodies, whereby it is provided that when an aeroplane body, by accident or other cause, lands upon the surface of the water, means are provided to keep the body afloat for a longer or shorter time.

With these objects in view, my invention consists of the following novel features of construction and arrangements of parts as are more particularly hereinafter described and pointed out in the claims, reference being had to the accompanying drawings, in which:

Fig. 1 is a side view of my device in perspective view.

Fig. 2 is an end view of my device as applied to an aeroplane, in cross section.

Fig. 3 is a side view of my device.

Fig. 4 is a side view of my device partly in cross section.

Fig. 5 is a side view of a fragmentary part of my device.

Fig. 6 is a side view of a modified form of my device.

Fig. 7 is a plan view of a modified form of my device.

Fig. 8 is a side view of a detailed part of my device.

The same reference characters denote like parts in each of the several figures of the drawings.

In carrying out my invention I have the aeroplane body A, and having mounted thereon the wing B and having also the usual propeller and mounted within the body A I have the cabin structure D.

As a further part of my invention I have constructed within the side walls of the aeroplane body A the hinged sections C. C. These sections are composed of an outer shell 2. 2 and mounted within the shell 2 I have an inner packing of cork 3. 3, conforming to the extent and outline of the outer surface 2, as shown in Fig. 2. This section C so construct-

ed is hinged to the main body of the aeroplane by the hinges 4. 4.

As a further part of my device, I have horizontally mounted a shaft 5, on which is mounted a drum or disk body 6, and mounted over the disk body 6, I have the winding chain 7 and 7', the outer ends of the chain 7 and 7' are connected in any convenient manner with the inner side of the filled hinged section C, at the point 8 and 8'. These sections are formed two on each side of the aeroplane body A, spaced apart so as to form on each side of the aeroplane body A, the two hinged sections C and C', as shown in Fig. 3, of the drawings. Also I have the front

shaft 5 and the rear shaft 5', on said aeroplane body A as shown in Fig. 3. In a modified form of my device, as shown in Fig. 4, I have mounted on shaft 5 and 5', at the inner ends of the same, a gear 9 and 9', and as a

further part of my device, in the modified form, I have at the inner edge the sections C and C', a shaft 10, to which the sections C and C' are hinged. On shaft 10 I have mounted the gear 9. 9', which may be slidably mounted upon the shaft 10; also mounted on the inner end of the shaft 10, I have the clutch 11, pivotally mounted to engage the gears 9. 9'; also as a further part of my device, I have the pivoted levers 12, 12, pivoted on the pivot 13, 13, and from the outer end of the pivoted levers 12. 12, pivoted on the shaft 13, 13, I have pivotally connected the curved lever 15, with the foot rest 16 thereon, and pivoted on the pivot 17. The

inner end of the pivoted lever 15, has pivotal connection at 18 with the inner levers 12. 12; the outer ends of the curved levers 14. 14 have pivotal connection with the clutch 11 at the point 19, and engaging said clutch at that point.

In the operation of the first form of my device, as shown in Figs. 1 and 2, when for any reason the aeroplane body A is about to enter on water, by operating the pulleys 6, 6, the

chains 7. 7 connected with the hinged sections C, draw the hinged sections outward horizontally so as to form a corked horizontal surface to sustain and support upon the 5 water surface the body of the aeroplane A. Also in the modified form of my device, as shown in Figs. 4, and Figs. 5, when the body of the aeroplane is about to enter the water, by pressing upon the foot rest 16, the piv- 10 oted levers 12. 12, which in turn move the sliding clutch 11, causing the gear 9 to be brought in connection with the gear 9'. 9', causing gears 9'. 9' to revolve and thereby turning shafts 10. 10 and thereby turning the 15 sections C and C' into an outward horizontal hinged position, the same as is accomplished by the chains 7 and 7', shown in Fig. 2 and thus forming a horizontal nonsinkable float- 20 ing surface projecting from the aeroplane body A, and to prevent the same from sinking.

As a further part of my device, and a modified form of the same, I have the structure, as shown in Figs. 6 and 7, and in this aeroplane 25 body A, and mounted thereon, I have horizontally pivoted, front and rear sections E. E, and the horizontally mounted sections E'. E'; and as a further part of the structure I have mounted within the aeroplane body A, 30 in any convenient manner the vertical shafts 20. 20, and on the outer surfaces of which I have mounted the coil spring structure 21. 21, surrounding the shafts, and at the upper end of which shafts the springs engage a head 35 structure 22. 22, mounted on shaft 20. 20. And also mounted in connection with it I have the pulleys 24. These pivoted heads 22. 22, have engagement with the inner portion or 40 ends of the horizontally mounted planes E. E, and E'. E'. Recessed in the heads 22. 22, I have the openings 23. 23, adapted to receive a turn handle or turn bar, and in connection with it I have a pawl and ratchet construction for holding in a coiled position the 45 springs 21. 21, and operating the turn heads 22. 22, and with it the pivotal wings E. E, and E'. E', respectively. In the operation, the pulleys 24. 24, being wound up by a turn bar or other means, and the aeroplane body 50 A drops to the water, from any cause, then by releasing the spring turned heads 22. 22, it causes them to revolve, and operates the pulley 24 and belt connection 25, mounted thereon, connected with the pulleys on the 55 under side of the pivotal planes E. E, and E'. E', and causes them to turn outward in horizontal alinement, to position shown in Fig. 7, and thus causing to be placed upon the water surface parallel extended floats 60 filled with nonsinkable substance, thereby causing the body A to float and having a tendency to support and sustain the body to float upon the water surface.

As a further part of my device, I have the 65 shaft 20 on which is mounted the ratchet 26,

also I have mounted on a standard "a", the shaft 27, and pulley thereon 28; also on shaft 20 I have the crank arm 29, also mounted on shaft 27, I have a hand lever 30 on which is mounted the spring pawl 31, which contacts 70 with a ratchet 32; also mounted on shaft 27, between pulley 28 and crank arm 29, I have a rod or cable b.

As a further part of my device, I have mounted on shaft 20 the ratchet 33, and also 75 at any convenient point I have mounted the pawl 34 to engage ratchet 33; also mounted in any convenient position I have the vertical spring lever 35, pivoted on pivot 37 and having connected therewith the coil spring 80 36, between this lever 35 and pawl 34, and connecting with lever 35, and pawl 34, I have the trip rod 38.

In the operation of my device the coil 85 spring 21, mounted on the shafts 20. 20, is wound up and tensioned by the operation of the lever and pawl 30 turning the pulley 28 and the rod or cable b, and thereby turning the crank arm 29, and ratchet 33 on shaft 20. The ratchet is held in tension by the 90 spring pawl 34, connected therewith as the winding proceeds, until by the turning of the shaft 20, the wings E. E, and E'. E', are drawn pivotally into place in horizontal position on the top of the body A, as shown 95 in Fig. 7. The wings are again released and unwound at any given time by operating the lever 35 and trip rod 38 and releasing pawl 34 from contact with the ratchet 33, and the shafts 20. 20 again revolve and with them 100 pulleys 24. 24, and connecting chains 25. 25, which out-turn the pivoted wings E. E, and E'. E'.

Having thus described my invention, what I claim as new and for which I desire Letters Patent is as follows:

1. In an aeroplane body, hollow adjacent, parallel, pivotally mounted sections on top of the aeroplane body, filled with nonsinkable substance, pivotal spring operated supports beneath and at the ends of the same, means for contracting said spring mounting for drawing said sections into pivotal horizontal alinement, and means for releasing said springs and projecting said wings into 110 parallel outward alinement at right angles to the side of the aeroplane body.

2. In an aeroplane body, opposing fore and aft side sections pivotally secured to said body adjacent the upper surface thereof, each section being hollow and filled with nonsinkable material, and normally disposed against the body when in inoperative position, and operating means for moving said sections away from the body into substantial horizontal relation with the upper surface of said body.

3. In an aeroplane body, hollow, adjacent, parallel, pivotally mounted sections near the top of the aeroplane body, said sections being 130

filled with buoyant material, pivotal spring
operated supports beneath said sections and
disposed at the ends of same, means for ten-
sioning said spring mounting for drawing
said sections into pivotal, horizontal align-
ment, releasing means for said springs where-
by said sections are projected outwardly into
parallel relationship at right angles to the
side of the airplane body and means for re-
tracting said sections into inoperative posi-
tion.

In testimony whereof I have affixed my
signature.

LOUIS NYCZ.
